DESIGN FOR A PORTABLE DEGREASING UNIT

Willard D. Phillips and Ralph A. Van Fosser,
Chicago, Ill., assignors, by direct and mesne as-
signments, to The Dow Chemical Company,
Midland, Mich., a corporation of Michigan

Application June 3, 1940, Serial No. 92,782

Term of patent 14 years

To all whom it may concern:

Be it known that we, Willard D. Phillips and Ralph A. Van Fosser, citizens of the United States and residents of Chicago, in the county of Cook and State of Illinois, have invented a new, original, and ornamental Design for a Portable Degreasing Unit, of which the following is a specification, reference being had to the accompanying drawing, forming part thereof.

Fig. 1 is an elevational view of a portable de-
greasing unit, showing our new design; and

Fig. 2 is a top plan view thereof.

We claim:

The ornamental design for a portable degreas-
ing unit, as shown.
